EXPANSIBLE ROTARY DRILL BITS

Archer W. Kammerer, Fullerton, Calif., assignor of one-fifth each to Jean K. Lamphere, Fullerton, Calif., and Archer W. Kammerer, Jr., Houston, Tex.

Filed July 26, 1962, Ser. No. 212,691

7 Claims. (Cl. 175—267)

The present invention relates to rotary drill bits, and more particularly to bits having expandable cutters for enlarging the diameters of well bores, milling out portions of casing strings in well bores, and the like.

Rotary expandible drill bits have been used having cutters expanded outwardly by the hydraulic pressure of fluid pumped down through tubular drilling strings to which the bits are secured. When the drill bit is of small size, the hydraulic area on which the fluid pressure acts may be insufficient to produce adequate total force for expanding the cutters outwardly against the formation to enlarge the diameter of the well bore, or outwardly against a surrounding well casing to sever the same. Even with drill bits of larger size, sufficient hydraulic pressure for expanding its cutters outwardly may not be present because of inadequacy of the pumps, or in very deep holes because of the very substantial diminution in fluid pressure caused by friction losses in pumping the fluid through comparatively long drilling strings.

An object of the invention is to provide an improved expandible rotary drill bit, in which the hydraulic force available for expanding its cutters is assisted by supplementary means to assure proper and full expansion of the cutters.

Another object of the invention is to provide an expandible rotary drill bit having cutters expandible outwardly by a combination of hydraulic and spring forces, in which a spring device can be embodied in the bit capable of exerting a comparatively great force.

A further object of the invention is to provide an expandible rotary drill bit having cutters expandible outwardly by a combination of hydraulic and spring forces, in which assembly of the spring in the bit under stress, as well as its disassembly, can be accomplished rapidly and with comparative ease.

An additional object of the invention is to provide an improved hydraulically operable, expandible rotary drill bit, in which the hydraulic force for expanding its cutters outwardly is assisted by supplementary means that maintain the cutters expanded upon relieving of the hydraulic force.

Yet a further object of the invention is to provide an expandible rotary drill bit having cutters expanded outwardly by a spring device, in which the cutters can still be shifted to their initial retracted position in the event difficulty is encountered in returning the spring to its initial position within the bit.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

FIGURE 1 is a longitudinal section through an expandible rotary drill bit, with its cutters occupying a retracted position;

FIG. 2 is a view similar to FIG. 1, disclosing the cutters in their outwardly expanded position.

2

A rotary expandible drill bit A is disclosed in the drawings, which is secured to the lower end of a string of drill pipe B extending to the top of a well bore D, by means of which the drill bit is lowered through a string of well casing C to a desired location where the cutters 10 of the bit are to be expanded outwardly. The drill bit specifically disclosed has milling type of cutters 10 to sever a casing section and mill it away along a desired length. Such cutters are illustrated by way of example only, and it is to be understood that other type of cutters, whether they be drag or roller types, can be used depending upon the operation to be performed in the well bore. The cutters illustrated can, if desired, be used for enlarging the diameter of the well bore D, as well as milling away a section of well casing C therewithin.

The upper portion of the rotary drill bit includes a mandrel 11 having an upper pin 12 threadedly connected to the lower end of the string of drill pipe B. This mandrel includes an upper kelly or drill stem member 13 slidably splined to the main body 14 of the bit. The exterior of the lower portion 15 of the kelly is non-circular in shape, being telescopically received in a companion non-circular socket 16 formed in the main bit body. Specifically, the kelly exterior and the socket may be of hexagonal shape to enable the kelly 13 to be moved longitudinally with respect to the body 14 while being capable of transmitting rotary motion to the body.

The mandrel 11 has a limited range of longitudinal movement within the body, its downward movement being determined by engagement of the lower end 17 of the kelly with an inwardly directed body shoulder 18, and its upward movement being limited by engagement of an external shoulder or piston portion 19 of the kelly with a cylinder head 20 secured to the body. The upper end of the head has a flange 21 engaging a body shoulder 22, the flange being prevented from moving upwardly of the body by split snap retainer rings 23 fitting in a body groove 24 and overlying the flange 21.

The body 14 has a plurality of expandible parts mounted on it. These include cutter supporting members 25 pivotally mounted in body slots 26 on hinge pins 27 suitably secured to the body to prevent their loss therefrom. Each cutter supporting member 25 depends from its hinge pin 27 and carries a suitable cutter structure 10, such as a drag or milling cutter, at its lower end, which, as stated above, has the purpose of severing and milling away a section of casing C, enlarging the diameter of a well bore D, or both.

The cutter supporting members 25 and the cutter structures 10 themselves normally occupy a retracted position substantially entirely within the confines of the main body 14 of the bit. These cutter supporting members and the cutter structure are expandible outwardly. In the use of the device illustrated in the drawings, their outward expansion can first sever the casing C and then mill it away by operating upon the upper end E of the casing therebelow, or the cutter can act upon the upwardly facing shoulder F which they form in the enlarged well bore D. To accomplish the expansion, each cutter supporting member 25 has an inclined expander surface 30 on its inner portion below the hinge pin 27 which tapers in a downward and inward direction. Each expander surface terminates in a lock surface 31 formed on a lock portion 32 of the cutter supporting member. The outward expansion is accomplished by producing relative longitudinal movement between the mandrel 11 and the bit body 14, which will produce relative longitudinal movement between the cutter supporting members 25 and the tubular member 33 of the mandrel. This tubular member includes a lower portion 34 slidable within a guide bushing 35 mounted

in a bridge 36 secured to the body and extending across the body slots 26. This guide bushing 35 is disposed below the lock portions 32 of the cutter supporting members 25.

Located initially substantially above the guide bushing and below the hinge pins 27 and in cutter member recesses 37 is a mandrel lock and expander 38 which has outer surfaces 39 adapted to engage the expander surfaces 30 and the lock surfaces 31. The lock and expander 38 may be formed integral with the tubular member 33, the upper end of the latter being piloted within a socket 40 formed in the lower portion 15 of the kelly. An enlarged boss 41 on the tubular member engages a downwardly facing shoulder 42 of the kelly, the tubular member 33 being held against this shoulder by a suitable split retainer or lock ring 43 mounted in an internal groove 44 encompassing the kelly socket 40 and engaging the lower end of the tubular member boss 41.

Drilling mud or other fluid can pass down through the central passage 45 of the kelly or drill stem and into the central passage 46 extending completely through the tubular member 33. Leakage of fluid around the exterior of the tubular member 33 is prevented by a suitable side seal ring 47 in the kelly which engages the exterior of the boss 41.

Assuming the body 14 of the tool to be elevated relatively along the tubular mandrel 11, the inclined expander surfaces 30 of the cutter supporting members 25 will be shifted upwardly along the lock and expander portion 38 of the tubular member 33. During such upward shifting, the cutter supporting members 25 and the cutter structures 10 carried thereby will be pivoted about the hinge pins 27 and urged in an outward direction. Upward movement of the body 14 with respect to the tubular mandrel 11 can continue until the cutter structures 10 have been shifted outwardly to their fullest extent, as determined by engagement of stop shoulders 50 on the cutter supporting members with companion shoulders 51 formed in the body on opposite sides of the body slots 26. When such engagement occurs, the lower end 17 of the kelly portion 13 of the tubular mandrel will engage the body shoulder 18, and the lock and expander 38 on the tubular member 33 will be disposed behind and in engagement with the lock portions 32 on the cutter supporting members 25.

Relative longitudinal movement between the tubular mandrel 11 and the body 14 of the tool is accomplished hydraulically. The enlarged piston portion 19 on the drill stem 13 is received within a counterbore 52 formed on an intermediate portion 53 of the body of the tool. This intermediate portion actually constitutes a cylinder having a cylindrical wall 54 extending from a lower shoulder 55 defining the bottom of the counterbore to the cylinder head 20.

A confined cylinder space 56 is formed between the piston portion 19 of the kelly, the periphery of the kelly 13 above the piston, and the cylinder 53. A suitable packing or side seal ring 57 may be disposed in the piston 19 which is adapted to slidably seal against the cylindrical wall 54 of the cylinder. Fluid is thereby prevented from passing in a downward direction between the piston 19 and the cylinder 53. Fluid is also prevented from passing in an upward direction from the annular cylinder space 56 by an inner side seal ring 59 carried in the cylinder head 20 and slidably and sealingly engaging the periphery of the kelly 13 above the piston 19, and also by an outer side seal ring 58 disposed in the head 20 and sealingly engaging the cylinder wall 54.

Fluid under pressure in the string of drill pipe B and in the tubular mandrel passage 45 can be fed into the cylinder space 56 through one or more side ports 60 establishing communication between the central passage through the kelly and the cylinder space. Such fluid under pressure is developed in the specific tool disclosed in the drawings by virtue of the fact that the pas-

sage 46 through the tubular member 33 of the mandrel 11 is of a restricted diameter, as compared to the passage 45 through the kelly portion 13 of the mandrel. As a result, the pumping of drilling mud, or other fluid, at an adequate rate through the apparatus will build up a back pressure of fluid in the passage 45, which pressure will be imposed on the fluid in the cylinder space 56, acting upon the cylinder head 20 to urge the body 14 of the tool in an upward direction with respect to the tubular mandrel 11, to secure outward expansion of the cutter supporting members 25 and cutter structures 10 to their fullest extent, as above described.

The upward movement of the body 14 of the tool with respect to the tubular mandrel 11 is assisted, in the apparatus illustrated in the drawings, by a spring 70 which adds its force to the hydraulic force acting upwardly on the cylinder head 20. As shown, the body 14 includes a spring housing portion 71 extending upwardly from the cylinder 53, which is spaced from the kelly 13 to provide an annular spring chamber 72 in which a helical compression spring 70 is disposed. The lower end of the spring bears against a thrust ring or flange 73 which is prevented from moving downwardly by resting upon an inherently contractable split retainer ring 74 disposed in a peripheral groove 75 in the kelly and extending outwardly therefrom. The upper end of the spring 70 bears against a spring seat 76 which is prevented from moving upwardly of the housing by engaging a split retainer ring 77 disposed in an internal groove 78 in the housing. In order to prevent entry of drilling mud, or other well bore fluid and substances, into the spring housing 71, a guide 79 is releasably inserted in the upper end of the housing, being retained in position by a split expandable spring-like ring 80 disposed in a groove 81 in the guide and received within an internal groove 82 in the upper end of the housing.

The spring is constantly exerting a force on the housing 71 and body 14 of the tool tending to elevate the latter along the mandrel 11 in order to effect outward expansion of the cutter supporting members 25 and cutters 10. Such upward movement can occur since an adequate space 83 is provided initially between the cylinder head 20 and the lower thrust ring 73, allowing upward movement of the body along the mandrel to the fullest extent, in which the body flange 18 engages the lower end 17 of the kelly 13.

The spring 70 is protected in its housing 71, the spring chamber 72 being of substantial radial width between the kelly 13 and the inner wall of the housing, allowing the cross-section of the spring turns to be made quite substantial, thereby allowing the use of a spring 70 having a large initial compressive force. When disposed in its initial position, the spring, for example, may exert a force of about 1,500 pounds tending to elevate the body 14 along the mandrel 11 of the tool. This force will supplement the force of the hydraulic pressure acting upon the pressure effective area of the cylinder head 20 and tending to elevate the body of the tool along the mandrel, and thereby effect outward expansion of the cutters 10.

In the operation of the apparatus A, it is run in the well casing, the cutter supporting members 25 and cutters 10 occupying their initial retracted position, despite the tendency of the spring 70 to expand the latter. The outer sides of the cutter supporting members 25 will merely slide along the inner wall of the casing C. When the desired location in the well casing is reached at which the casing severing action or hole enlarging operation is to commence, the drill string B and the rotary drill bit A are turned at the desired rate of speed and the pumps at the top of the well bore started to pump fluid at a sufficient rate through the drill pipe and into the mandrel passages 45, 46, building up a back pressure in the kelly passage 45 and of the fluid in the ports 60 and cylinder space 56, which pressure acts upon the cylinder head 20 to urge the body 14, the cutter supporting members 25,

and the cutter structures 10 in an upward direction with respect to the mandrel 11. Such upward movement is assisted by the force exerted by the spring 70, which spring force can, as in the example given above, be quite considerable. During upward movement of the body 14 relative to the mandrel 11, the expander surfaces 30 are brought to bear against the lock and expander portion 38 of the mandrel, the cutter structures 10 being urged in an outward direction against the wall of the well casing C, and gradually milling it away. During this operation, the apparatus A is retained in substantially the same longitudinal position in the well casing. As the casing is cut away, the hydraulic force and the spring force acting upon the body 14 raises the latter and the cutter supporting members 25 and cutter structures 10 to a further extent until the cutters have completely severed the casing C. Continued rotation of the drill pipe B and the pumping of fluid through the drill bit will cause the cutters 10 to cut away additional casing and dig into the formation, the spring force and hydraulic force combining to expand the cutters outwardly, until the cutters 10 have been expanded outwardly to their fullest extent, as determined by engagement of the stop shoulders 50, 51 with one another and the lower end 17 of the kelly portion of the mandrel with the body shoulder 18. With the parts in this position, the lock portion 32 of each cutter supporting member 25 will bear against the lock and expander portion 38 of the tubular member 33 to preclude inadvertent partial retraction of the cutter structures 10 from their fully expanded position.

Downweight in a proper amount can now be imposed on the string of drill pipe B, which downweight is transmitted through the kelly 13 to the body shoulder 18, and from the body to the stop shoulders 50, 51 directly to the cutter supporting members 25 and the cutter structures 10, urging the cutter structures against the upwardly facing severed end E of the well casing and against the upwardly facing formation shoulder F. The imposition of a proper downweight or drilling weight on the apparatus and its rotation at a proper speed will cause the cutters 10 to act upon the severed end E of the casing and the shoulder F to mill the casing away, and also to drill away the formation shoulder. During such milling and drilling actions, drilling fluid is being pumped down through the drill pipe in the apparatus, discharging from the latter and carrying the casing cuttings and formation cuttings upwardly around the tool A and the drill pipe B to the top of the hole.

After the desired length of casing C and hole D have been cut and drilled away, the tool can be withdrawn from the well bore. Pumping of fluid can cease and the drill pipe B and the drill bit A elevated in the well bore D. The spring 70 will retain the body 14 upwardly along the mandrel 11, so as to maintain the cutters in their outward expanded position, until the cutter supporting arms 25 engage the downwardly facing shoulder H provided by the upper severed end of the casing C, which will tend to prevent further upward movement of the tool. Accordingly, the taking of a sufficient upward strain on the drill pipe B and mandrel 11 will cause the mandrel to move upwardly within the body 14 against the force of the spring 70, compressing the latter and elevating the lock portion 38 of the mandrel above the lock and expander surfaces 31, 30 of the tool, allowing the cutter supporting members 25 and cutters 10 to shift inwardly entirely within the confines of the body 14 and the casing C. The tool, with the cutters in retracted position, can now be elevated through the casing to the top of the well bore, the cutter supporting members 25 merely sliding along the inner wall of the well casing C.

In the absence of the spring 70, in the event the cutter members 25 were elevated from the upwardly facing casing end E and the shoulder F, and the pump pressure ceased, the body 14 of the tool would tend to drop downwardly along the mandrel 11 and the cutters 10 could

then shift to a retracted position. However, with the spring 70 constantly exerting a force holding the body 14 in its upward position with respect to the mandrel 11, the relieving of the hydraulic pressure will not result in the cutters 10 shifting to a retracted position. Instead, they will remain in their outwardly expanded position, such as disclosed in FIG. 2.

In relatively small size tools, the effective area of the cylinder head 20, as compared to the hydraulic pressure available for action upon such head, may be insufficient to insure the exertion of sufficient outward force of the cutters 10 against the casing C to sever the latter upon rotation of the drill pipe B and the drill bit A, or to enlarge the diameter of the well bore D by bearing against the wall of the formation. Such ineffective fluid pressure may not only be due to the relatively small annular area of the cylinder head, but to the unavailability of adequate pumps at the top of the well bore capable of supplying sufficient pressure. Even where large capacity and relatively high pressure pumps are available, the use of the drill bit A at the lower end of a very long string of drill pipe B is associated with very substantial losses in fluid pressure due to the frictional resistance of the fluid flowing through the pipe itself. In all of such instances where hydraulic force may be inadequate, the presence of the comparatively strong compression spring 70 acting between the mandrel 11 and body 14 of the tool will insure the supplementing of the hydraulic force, and the presence of an adequate total force effecting full outward expansion of the cutters 10 for the purpose of fully severing the well casing C, or enlarging the well bore D to its fullest extent, or both, the body 14 being elevated along the mandrel 11 to its fullest extent at which the lock portion 38 will hold the cutter supporting members 25 and cutters 10 in their outward expanded position.

The spring 70 is readily assembled in the tool and disassembled therefrom, being insertable in place through the upper end of the housing portion 71 against the lower thrust ring or flange 73. Through use of a suitable spring compression tool, the spring seat 76 is placed on top of the spring and forced toward the thrust ring or flange 73 to compress the latter, whereupon the retaining ring 77 is inserted in place, overlying the upper spring seat 76 and snapped into its groove 78. The annular guide 79 can then be mounted in place. The spring will shift the body 14 upwardly along the mandrel 11 to expand the cutters. To prevent such expansion and to start the tool in the casing C, a holding screw 90 may be threaded in a hole 91 in the body, the screw overlying the guide 79 and thereby preventing the spring 70 from expanding. Following inserting of the cutters 10 and supporting members 25 in the casing C, the screw 90 may be removed and the tool A lowered in the casing.

When disassembly is desired, the annular guide 70 is easily removed in an upward direction from the upper end of the housing 71, and a suitable tool provided for shifting the spring seat 76 downwardly to a slight extent to relieve the annular ring 77 of the spring force, allowing the latter to be retracted from its groove 78 and removed from the housing, whereupon the spring force 70 can be gradually released and the spring 70 also removed from the housing.

Assurance is had that the cutters 10 can be shifted to a retracted position from their fully expanded position, despite the fact that it might not be possible, due to foreign substances in the spring chamber 72, for example, to recompress the spring 70 back to its initial position after it has expanded and shifted the body 14 upwardly along the mandrel 11 to its fullest extent, such as disclosed in FIG. 2. To accomplish this purpose, the lower side 92 of the groove 75 containing the split retainer ring 74 against which the thrust ring 73 bears can be tapered in an upward and inward direction, engaging the lower end of the retainer ring. This ring 74 inherently tends to remain in an inward position and is

of such dimensions as to resist its outward expansion from the groove 75. The exertion of a sufficient upward force on the mandrel 11 of the tool will cause the tapered side 92 of the groove to engage the ring and shift it outwardly from the groove, thereby disconnecting the mandrel 11 from the ring 74 and allowing the mandrel to move upwardly in the housing 71, which will shift the mandrel lock 38 above the companion lock portions 32 of the cutter supporting arms 25, allowing the cutters 10 to shift inwardly to their initial retracted position. The angle of taper of the bottom side 92 of the groove, and the resistance of its outward expansion offered by the ring 74, are such that several times the maximum force exerted by the spring 70 is required to effect shifting of the retainer ring 74 from the groove 75. If, for example, the maximum force exerted by the spring is about 1,500 pounds, the upward force on the mandrel 11 required to shift the ring 74 from its groove 75 may be of the order of about 5,000 pounds, thereby assuring that the retainer ring will normally remain within the groove and serves as an abutment for the thrust ring or flange 73. It is only under emergency conditions, in which retraction of the cutters 10 cannot take place as a result of inability to recompress the spring 70, that the taking of a sufficient upward pull on the mandrel 11 will expand the retainer ring 74 from its groove 75 and thereby release the mandrel from the thrust ring 73, allowing the mandrel to move upwardly within the body 14 to a position allowing full retraction of the cutters 10.

I claim:

1. In a rotary well drilling bit: a main body; cutter means mounted on said body for expansion laterally outward of said body; a mandrel connectible to a drill string and slidably splined to said body, whereby drilling torque is transmitted from said mandrel to said body; coengagable expander means on said mandrel and cutter means; said body having a cylinder portion above said expander means slidably and sealingly engaging said mandrel; said mandrel having a fluid passage communicating with the drill string and cylinder portion to feed fluid under pressure to said cylinder portion to elevate said body and cutter means with respect to said mandrel to cause said expander means to expand said cutter means laterally outward; and a helical compression spring in said body above said cylinder portion and surrounding said mandrel and acting upon said mandrel and body for elevating said body and cutter means with respect to said mandrel to cause said expander means to expand said cutter means laterally outward.

2. In a rotary well drilling bit: a main body; cutter means mounted on said body for expansion laterally outward of said body; a mandrel connectible to a drill string and slidably splined to said body, whereby drilling torque is transmitted from said mandrel to said body; coengagable expander means on said mandrel and cutter means; said body having a cylinder portion above said said expander means slidably and sealingly engaging said mandrel; said mandrel having a fluid passage communicating with the drill string and cylinder portion to feed fluid under pressure to said cylinder portion to elevate said body and cutter means with respect to said mandrel to cause said expander means to expand said cutter means laterally outward; said body having a housing portion above said cylinder portion in spaced relation to said mandrel; and spring means in said housing portion acting upon said mandrel and housing portion for elevating said body and cutter means with respect to said mandrel to cause said expander means to expand said cutter means laterally outward.

3. In a rotary well drilling bit: a main body; cutter means mounted on said body for expansion laterally outward of said body; means for expanding and holding said cutter means laterally outward, said expanding and holding means comprising a mandrel connectible to a drill string and slidably splined to said body, whereby drill-

ing torque is transmitted from said mandrel to said body; said body having a housing portion spaced laterally from said mandrel; spring means in said housing portion acting upon said mandrel and housing portion for elevating said body and cutter means with respect to said mandrel to hold said cutter means laterally outward; and means releasably securing said spring means to said mandrel and being releasable in response to a predetermined force imposed thereon by said mandrel to enable said mandrel to move upwardly with respect to said body and cutter means and allow said cutter means to move laterally inwardly to retracted position.

4. In a rotary well drilling bit: a main body; cutter means mounted on said body for expansion laterally outward of said body; means for expanding and holding said cutter means laterally outward, said expanding and holding means comprising a mandrel connectible to a drill string and slidably splined to said body, whereby drilling torque is transmitted from said mandrel to said body; said body having a housing portion spaced laterally from said mandrel; a thrust member surrounding said mandrel; means releasable in response to a predetermined force imposed thereon by said mandrel releasably securing said thrust member to said mandrel; a seat member secured to said housing portion; and a helical compression spring in said housing portion bearing against said members to elevate said body and cutter means with respect to said mandrel to hold said cutter means laterally outward; release of said releasable means enabling said mandrel to move upwardly with respect to said body and cutter means and allow said cutter means to move inwardly to retracted position.

5. In a rotary well drilling bit: a main body member; cutter means mounted on said body member for expansion laterally outward of said body member; means for expanding and holding said cutter means laterally outward, said expanding and holding means comprising a mandrel member connectible to a drill string and slidably splined to said body member, whereby drilling torque is transmitted from said mandrel member to said body member; said body member having a housing portion spaced laterally from said mandrel member; spring means in said housing portion acting upon said mandrel member and housing portion for elevating said body member and cutter means with respect to said mandrel member to hold said cutter means laterally outward; and means releasably securing said spring means to one of said members and being releasable in response to a predetermined force imposed thereon by said mandrel member to enable said mandrel member to move upwardly with respect to said body member and cutter means and allow said cutter means to move laterally inwardly to retracted position.

6. In a rotary well drilling bit: a main body; cutter means mounted on said body for expansion laterally outward of said body; a mandrel connectible to a drill string and slidably splined to said body, whereby drilling torque is transmitted from said mandrel to said body; coengagable expander means on said mandrel and cutter means; said body having a cylinder portion above said expander means slidably and sealingly engaging said mandrel; said mandrel having a fluid passage communicating with the drill string and cylinder portion to feed fluid under pressure to said cylinder portion to elevate said body and cutter means with respect to said mandrel to cause said expander means to expand said cutter means laterally outward; said body having a housing portion above said cylinder portion in spaced relation to said mandrel; a thrust member surrounding said mandrel; means releasable in response to a predetermined force imposed thereon by said mandrel releasably securing said thrust member to said mandrel; a seat member secured to said housing portion; and a helical compression spring in said housing portion bearing against said members to elevate said body and cutter means with respect to said mandrel to cause

said expander means to expand said cutter means laterally outward.

7. In a rotary well drilling bit: a main body; cutter means mounted on said body for expansion laterally outward of said body; a mandrel member connectible to a drill string and slidably splined to said body, whereby drilling torque is transmitted from said mandrel member to said body; coengagable expander means on said mandrel member and cutter means; said body having a cylinder portion above said expander means slidably and sealingly engaging said mandrel member; said mandrel member having a fluid passage communicating with the drill string and cylinder portion to feed fluid under pressure to said cylinder portion to elevate said body and cutter means with respect to said mandrel member to cause said expander means to expand said cutter means laterally outward; said body having a housing member above said cylinder portion in spaced relation to said mandrel member; spring means in said housing member acting upon

5 said mandrel member and housing member for elevating said body and cutter means with respect to said mandrel member to hold said cutter means laterally outward; and means releasably securing said spring means to one of said members and being releasable in response to a predetermined force imposed thereon by said mandrel member.
